WASHING MACHINE

Fred A. Conterman, Jamestown, N. Y., assignor
to Blackstone Manufacturing Company, Inc.,
Jamestown, N. Y., a corporation of New York

Application August 22, 1936, Serial No. 97,429

9 Claims. (Cl. 74—387)

This invention relates to an improvement in wringers for washing machines and more particularly to a drive and control mechanism therefore.

5 The preferred embodiment of the invention discloses a wringer support, adaptable for use with a washing machine, which includes a reverse gear mechanism, indexing mechanism and means for preventing simultaneous action of these mechanisms.

More particularly the invention is directed to and has for its object the provision of a drive head and wringer support of simple and economical construction.

15 Another object of the invention is to provide, in conjunction with reversible drive head and wringer indexing mechanisms, an interlocking means whereby the wringer drive mechanism cannot be operated or reversed during indexing, or 20 indexing take place when the drive mechanism is in operative position.

Another object of the invention is to provide a reversing drive mechanism which can be readily assembled or disassembled, due to the simple arrangement of parts.

Another object of the invention is to provide a one piece housing for a reversible drive mechanism.

Another object of the invention is to provide 30 a housing which is adapted to fit and blend with the contour of the wringer casing for the purpose of eliminating unnecessary projections and enhance the appearance of the structure as a whole.

Other and further objects of the invention will 35 be more fully understood from a consideration of the following specification, taken in conjunction with the accompanying drawings in which

Fig. 1 is a fragmentary side elevation of a combined washing machine and wringer, including a 40 wringer drive and indexing head;

Fig. 2 is an enlarged vertical sectional view of the drive head, being taken substantially on the line 2—2 of Fig. 3;

45 Fig. 3 is an enlarged fragmentary sectional view of the drive head, being taken substantially on the line 3—3 of Fig. 2;

Fig. 4 is an enlarged vertical sectional view showing an interlock between the reversing drive 50 and indexing mechanism, being taken substantially on the line 4—4 of Fig. 3;

Fig. 5 is a fragmentary vertical sectional view 55 similar to Fig. 4, showing the indexing mechanism locked and the drive head in position for use;

Fig. 6 is a plan view of the drive head;

Fig. 7 is a perspective view of the drive head reversing lever;

Fig. 8 is a perspective view of a shifter block 5 movable by manipulation of the reversing lever;

Fig. 9 is a perspective view of the indexing lever;

Fig. 10 is a vertical sectional view, taken substantially on the line 10—10 of Fig. 3, showing stop means for the indexing lever; and

10 Fig. 11 is a horizontal sectional view, taken substantially on the line 11—11 of Fig. 1 and shows all positions into which the head and wringer may be swung.

Reference is now had to the drawings and 15 more particularly to Figures 1 and 2 thereof wherein a washing machine generally indicated by the reference numeral 10 is provided with a wringer 11 supported by a housing 12. The housing 12 is in turn mounted on a drive housing 13 20 which extends downwardly of one side of the washing machine 10.

The housing 13 encloses a drive shaft 14 connected in any suitable manner with the mechanism utilized to operate the washing machine. 25 The upper end of the housing 13 is of sufficient thickness to accommodate sockets 15 which may be arranged in a circle 90 degrees apart. A further socket 16 is located midway between one pair of sockets 15. These sockets constitute a 30 part of the indexing mechanism hereinafter fully described.

The housing 12 which encloses the wringer driving and indexing mechanisms is formed with 35 a downwardly directed annular collar 20 adapted to fit upon the upper end of the housing 13. Within the housing adjacent the collar 20 is a web portion 21 providing a bearing 22 in which a shaft 24 is mounted. The lower end of the shaft 24 is connected with drive shaft 14. The upper end of the shaft 24 is fitted with a pinion gear 25 which projects upwardly into a compartment 26 of the housing 12. Projecting inwardly from the end wall 27 of the housing is a boss 29 45 in which an opening 30 is made. The boss 29 is opposite the open end of the housing and is adapted to receive and support one end of a reverse gear shaft 31. The top wall 33 of the housing is formed with an inwardly directed reinforced portion 34 through which an opening 35 is made connecting the interior with the exterior 50 of the housing. Adjacent to and formed integral with portion 34 is a vertical wall 36. An opening 37 is made in this wall, said opening being on 55

center with the opening 30 of boss 29. A cover plate 39 is adapted to close the opening 37. This cover plate is annular and abuts an annular shoulder 40 provided therefor in the wall 36. 5 The plate 39 is formed with a plurality of arms 41 having suitable openings to receive screws 42 which have threaded engagement with the wall 36 and serve to secure the plate in place. Centrally of the plate 39 is an opening 44 which constitutes a further bearing for shaft 31. The free end of shaft 31 is fitted with a drive pin 45 with which a sleeve 46 is engaged. The other end of the sleeve 46 is slotted to engage a further pin 47 of a wringer shaft 48. Provision of sleeve 46 10 makes possible convenient assembly and disassembly of wringer and drive head.

That portion of the shaft 31 lying within the compartment 26 is fitted with pins 49. A twin gear 51 is mounted on the shaft 31 and includes 20 opposed sets of teeth 52, either set of which is engageable with the pinion gear 25. The opening in the gear 51 is formed with oppositely disposed key ways 53 into which the ends of pins 49 project. It is to be understood that the diameter of 25 the gear 51 is slightly less than the diameter of the opening 37, thus permitting inserting this gear through said opening during assembly.

Located on top of the housing 12 is a reversing lever 55. Within the opening 35 of the portion 34 is a shaft 56 from which projects a pin 57. The lever 55 is mounted upon and secured to this pin. Midway of the shaft 56 is an annular groove 59 in which at predetermined positions, depressions 60 are made. An opening 61 is made 30 in portion 34. In this opening is a bullet nosed pin 62 which is normally engaged with the annular groove 59 and one of the depressions 60, due to contact with a spring 64. Pressure of the spring 64 upon the pin 62 is varied by adjustment 35 of a screw 65 which is threaded into the outer end of the opening 61. In this connection it is to be understood that shaft 56 may be rotated by rotation of lever 55 and the bullet nosed pin 62 will move out of a depression 60, but the enlarged 40 portion thereof will not move out of the groove 59, thereby preventing inadvertent removal of shaft 56 from the housing 12. Projecting downwardly from the lower end of shaft 56 is an off center pin 67, on which a roller 68 is mounted. 45 When the lever 55 is rotated in one direction to a point 90 degrees from the position shown in Figure 2 of the drawings, roller 68 moves to the left. Conversely, when the lever 55 is moved in the opposite direction 90 degrees, roller 68 moves to 50 the right.

Reference is now had more particularly to further interior structure of housing 12 (see Fig. 3). Between the top wall 33 and web portion 21 of the housing and projecting inwardly from each 55 side wall 69 thereof is a ledge or shoulder 70. Mounted transversely of the housing with the ends resting upon ledges 70 is a shifter block 71. This block (see Fig. 8) is a channel shaped member and comprises a base wall 72 and side walls 66 73. At one end the base wall is formed with a slot 75. Adjacent the other end the wall 72 is formed with an inwardly raised projection 76. One edge 77 of the projection constitutes a stop to prevent movement of the roller 68 transversely of the 70 housing 12 in one direction and full rotation of the reversing lever 55. The shifter block, although mounted on and movable along ledges 70, projects between the spaced sets of teeth 52 of the twin gear 51. Inasmuch as the gear 51 is movable axially of its supporting shaft 31 it is evi-

dent that manipulation of the lever 55 will move the eccentrically mounted roller 68, block 71 and gear 51 from neutral position shown in Figure 2 to driving position in either direction.

One of the side walls 69 of the housing 12, 5 commencing adjacent the lower end of collar 20 and projecting upwardly to a point slightly beneath one of the ledges 70, is formed with an enlarged portion 80 in which a cylindrical opening 81 is made. This opening commences at the lower 10 end of the collar 20 and projects to adjacent the upper end of the portion 80, continuing there-through in a reduced diameter opening 82. Mounted in the opening 81 is an indexing pin 84. The lower end of this pin projects beneath the 15 collar 20 and is adapted to register with one of the sockets 15 or 16 formed in the housing 13. The upper end of the pin 84 is of reduced diameter to form an extension 85 which projects through the opening 82. Between the upper end 20 of the opening 81 and the upper end of pin 84 is a spring 87, which normally exerts a pressure on pin 84 to move it downwardly out of opening 81. The upper end of extension 85 is, under conditions hereinafter fully described, projectible 25 either against the under face of the base wall 72 of shifter block 71 or into the recess 75.

On that portion of the housing 12, heretofore designated as collar 20, is an indexing lever 90. This lever is mounted on a shaft 91 that extends 30 through collar 20 into portion 80, through a suitable opening 93. The shaft 91 is formed with a pair of slots 95 and 96. The base wall of each slot is shown to be at a 45 degree angle to the center line of the lever 90. A stop pin 97 is 35 mounted in the collar 20 of the housing and projects through slot 95. Referring to Figure 10, it will be noted that the pin 97 limits the indexing lever 90 to a 90 degree turn, an edge of the slot striking the pin in either dotted or solid line position of this figure. Slot 96 is of sufficient width to receive pin 84. The edge 99 of the base wall of this slot serves as a shoulder which engages the upper wall 100 of a slot 101 formed transversely of pin 84. Rotation of the lever 90 from 40 a vertical to a horizontal position causes shoulder 99 of shaft 91 to engage wall 100 of the indexing pin 84, moving said pin upwardly a determined distance against tension of spring 87. When the lever 90 is in a horizontal position, the lower end 45 of pin 84 has been withdrawn from one of the sockets 15 or 16 in the housing 13, thus allowing housing 12 and wringer 11 to swivel about shaft 14 to any desired position. Generally speaking, there are five wringer positions, one in 50 which the wringer is centered over the top of the washing machine. This position is obtained by locating the indexing pin 84 in socket 16. The other four sockets facilitate setting the wringer in any one of four predetermined positions 55 60 degrees apart.

As mentioned above, the housing 12 is open opposite the end wall 21. The side walls 69 of the housing are shaped to fit the contour of the flume board and clothes guide of the wringer 11 so 65 that when the wringer is engaged with the housing the entire structure will have a one piece appearance. Referring particularly to Figure 2 it will be noted that a plate 103 is secured to the end wall of the wringer 11. This plate is formed 70 with an opening 104, through which the wringer shaft 48 projects. The lower end of the plate is formed with a horizontal flange 105, the width of this flange being substantially that of the interior width of the housing 12. The upper end of plate 75

103 is formed with an outwardly and upwardly curved flange 107 which provides a pocket 108. Adjacent the upper wall 33 of the housing 12 and secured in any suitable manner to the side walls 59 of the housing is a supporting rod 109. Adjacent the lower edge of each side wall of the housing is a lug 110 having a drilled and tapped opening 111 therethrough.

Assembly of the wringer support and reverse drive head above described is as follows: After the indexing lever 90 and pin 84 have been assembled in the housing 12, said housing is mounted upon housing 13, collar 20 resting on the upper end of housing 13. Shaft 24 with pinion gear 25 thereon is placed within the compartment 26 and moved downwardly through the bearing 22 of the web portion 21. The lower end of shaft 24 is slotted to engage a pin on the upper end of the drive shaft 14. The shifter block 71 is next placed within the housing 12 and mounted on ledges 70. The twin gear 51 is now projected through opening 37 and moved to receive shifter block 71 between opposed sets of teeth 52. The gear 51 is, of course, positioned directly over pinion gear 25. The shaft 31 is next projected into the housing through gear 51 into the opening 30 of boss 29. The cover plate 39 is next applied to close opening 37. This plate is slid onto shaft 31, opening 44 therein being for this purpose. When the circumferential edge of the plate is moved into abutment with the annular shoulder 40 of the wall 36, screws 42 may be inserted through arms 41 to secure the plate to the wall. Roller 68, being of a diameter less than that of the opening 35 in the reinforced portion 34, is dropped through said opening into the shifter block 71. Shaft 56 is projected downwardly through opening 35 and moved so that the off center pin 61 thereof will project into an opening in the roller 68. The reverse lever 55 is mounted upon pin 57 which projects upwardly above the housing. The bullet nosed pin 62 is next inserted into the opening 61 and projected into the annular groove 59 of shaft 56. Pin 62 prevents shaft 56 from being inadvertently withdrawn by the lever 55 from its position in the housing 12 since it is never entirely removed from the annular groove 59 due to tension of spring 64 applied through screw 65. Shaft 91, which mounts indexing lever 90, having been assembled into the housing 12 at the time of assembling the indexing pin 84, the drive and indexing mechanisms are complete and assembly of the wringer 11, only remains before the device can be operated. The wringer 11, is mounted on the housing 12 by engaging the hook like flange 107 beyond the supporting pin 109 and swinging flange 105 of the plate 103 into position within the housing beneath lugs 110. Screws 112 are engaged through threaded openings in the flange with lugs 105 and prevent displacement of the wringer. The wringer shaft 48 is projected into sleeve 46, mounted on shaft 31, pin 47 serving to couple shaft 48 with the sleeve.

65 The drive and indexing mechanisms and wringer mounting having been fully described, operation and control of the device is as follows. In use the wringer may be swung to any of the four positions indicated by sockets 15. To accomplish this, indexing lever 90 must be moved from a vertical to a horizontal position. As explained above, shaft 91 of the lever 90 rotates the shoulder 98 thereof, moving indexing pin 84 upwardly against tension of spring 87. The indexing pin 84, it will be noted, can only be moved

upwardly to become disengaged from one of the sockets 15 or 16, if and when the shifter block 71 is in neutral position. That is to say, when neither set of teeth 52 of gear 51 is engaged with the pinion gear 25. With the shifter block in neutral position, slot 75 thereof is centered with the extension 85 of indexing pin 84 and through action of the lever 90 said extension moves upwardly into the slot (see Fig. 4). With the extension 85 projecting through shifter block 71, the block cannot be moved laterally along ledges 70 to bring either of the sets of teeth 52 into mesh with gear 25 through manipulation of the reversing lever 55. It is, therefore, evident that, when the wringer is released for pivotal movement, the drive mechanism thereof cannot be set in motion. After the wringer has been swung to the desired position, the lever 90 is rotated from horizontal to vertical position and indexing pin 84 is released to move downwardly into one of the sockets 15 under tension of spring 87. Withdrawal of the extension 85 of pin 84 from shifter block 71 releases the reversing lever 55. When this lever is rotated 90 degrees, eccentric roller 68 moves the shifter block 71 laterally along ledges 70, causing one of the sets of gears 52 to engage pinion 25 (see Fig. 5). With the parts in this position it will be noted that the slot 75 of the shifter block 71 is not in alignment with the extension 85 of indexing pin 84. Consequently, the indexing lever 90 cannot be manipulated to withdraw pin 84 from one of the sockets 15 while the reversing mechanism is in gear. This arrangement of parts prevents accidental swinging of the wringer while the rolls are in motion and conversely prevents the rolls being set in motion during swiveling of the wringer.

It will be noted that the assembly features of the driving and indexing mechanisms within the housing 12 are readily accessible through the open end of the housing and that this opening is closed by the wringer 11. Inasmuch as wringer 11 is readily disassembled from the housing 12 by removal of screws 112, access to all parts of the mechanisms embodied in this invention is readily had.

Although applicant has shown and described only one modification of index and drive mechanisms mounted in a housing adapted to support a wringer, it will be apparent to those skilled in the art that other modifications or adaptations of this structure may be made and are contemplated in so far as these modifications or adaptations are within the spirit and scope of the invention as defined in the hereunto annexed claims.

Having thus set forth my invention what I claim as new and for which I desire protection by Letters Patent is:

1. In a reverse gear structure for a wringer, an open ended housing, walls within the housing forming a gear enclosing compartment, one of the walls adjacent the open end of said housing having an opening of a diameter to permit insertion and removal of the gears of the structure, a cover plate for said opening, and means securing said cover plate to the walls of said opening.

2. In a reverse gear structure for a wringer, a housing adapted to support a wringer, a reverse gear mechanism in the housing adapted for operative connection to the wringer, a reversing lever on the housing, a shaft, projecting through an opening in the housing, mounting the lever, means connecting the lever shaft with the gear mechanism, further means in the housing, the

further means securing the lever shaft against removal from the housing and serving to indicate engaged or disengaged positions of the gear mechanism when the reversing lever is operated.

5. 3. In a reverse gear structure for a wringer, a housing adapted to support a wringer, walls within the housing forming a reverse gear enclosing compartment, one of the interior walls having an opening of a diameter to permit insertion of a reverse gear mechanism, a reversing lever on the housing having a shaft projecting into the compartment, eccentric means operably connecting the lever shaft with a reverse gear mechanism, further means securing the lever shaft against removal from the housing, the further means also serving to indicate engaged and disengaged positions of the gear mechanism when the reversing lever is operated.
4. In a reverse gear structure for a wringer, a housing adapted to support a wringer, walls within the housing forming a reverse gear enclosing compartment, one of the interior walls having an opening of a diameter to permit insertion of a reverse gear mechanism, a cover plate for the interior wall opening, the cover plate having an opening, the walls of which constitute a bearing for a reverse gear shaft, a reversing lever on the housing having a shaft projecting into the compartment, means in the housing exteriorly of the compartment securing the lever shaft against removal, the means cooperating with the shaft to indicate engaged or disengaged positions of the gear mechanism when the reversing lever is operated.

5. In a reverse gear structure for a wringer, a reverse gear housing adapted to support a wringer, a drive shaft housing on which the gear housing is rotatable about a vertical axis, a reverse gear mechanism in the gear housing, comprising a shaft, a pair of reversing gears on the shaft, a drive shaft pinion gear engageable with either of the reversing gears, a reversing lever on the gear housing, shifter means connecting the lever with the reversing gears, means in the gear housing engaged with the drive shaft housing, an indexing lever connected with and adapted to disengage the means from the drive shaft housing to permit rotation of the gear housing and wringer, the means in the gear housing, when disengaged from the drive shaft housing, being engaged with the shifter means to prevent adjustment of the reversing gears into operative position.

6. In a reverse gear structure for a wringer, a reverse gear housing adapted to support a wringer, a drive shaft housing on which the gear housing is rotatable about a vertical axis, a reverse gear mechanism in the gear housing, comprising a shaft, a pair of reversing gears on the shaft, a drive shaft pinion gear engageable with either of the reversing gears, a reversing lever on the gear

housing, a shifter block located between the reversing gears, the block being mounted on the housing and movable axially of the shaft, a rod connecting the lever with the block, means in the gear housing projecting into an opening in the drive shaft housing and securing the housings against relative rotation, an indexing lever, on the gear housing, connected with and adapted to move the means out of engagement with the drive shaft housing into engagement with the shifter block when the block is in neutral position.

7. In a reverse gear structure for a wringer, a reverse gear housing adapted to support a wringer, a drive shaft housing on which the gear housing is rotatable about a vertical axis, a reverse gear mechanism in the gear housing comprising a shaft, a pair of reversing gears on the shaft, a drive shaft pinion gear engageable with either of the reversing gears, a reversing lever on the gear housing, shifter means connecting the lever with the reversing gears, these shifter means being located within the gear housing and movable axially of the shaft, a vertically movable pin mounted in the gear housing, the pin projecting into an opening in the drive shaft housing and securing the housings against relative rotation, an indexing lever, on the gear housing, connected with and adapted to move the pin out of engagement with the drive shaft housing, the pin, when disengaged from the drive shaft housing, being engaged with the shifter means to prevent adjustment of the reversing gears into operative position.

8. In a reverse gear structure for a wringer, a housing having an open end, the walls of which conform to and are adapted to fit the end contour of said wringer, a further wall within the housing adjacent the open end thereof, said further wall having an opening of a size to permit insertion and removal of the gears of the structure, a cover plate for said opening, and means securing said cover plate to the walls of said opening.

9. In a reverse gear structure for a wringer, a reverse gear housing adapted to support a wringer, a drive shaft housing on which the gear housing is rotatable about a vertical axis, a reverse gear mechanism in the gear housing, a reversing lever mounted on the housing, shifter means connecting the lever with the reverse gear mechanism, a vertically movable rod in said gear housing, an indexing lever connected with and adapted to move said rod, said rod in one position being engaged with said shifter means to prevent movement thereof, and in the other position with an opening in said shaft housing whereby to prevent relative rotation of said reverse gear housing and said drive shaft housing.

FRED A. CONTERMAN.
